UNITED STATES PATENT OFFICE.

ROBERT L. CARR, OF FALL RIVER, MASSACHUSETTS.

WARPING-MACHINE.

SPECIFICATION forming part of Letters Patent No. 276,667, dated May 1, 1883.

Application filed November 14, 1882. (No model.)

To all whom it may concern:

Be it known that I, ROBERT L. CARR, of the city of Fall River, in the county of Bristol and State of Massachusetts, have invented certain new and useful Improvements in Warping-Machines; and I do hereby declare that the following specification, taken in connection with the drawings furnished and forming a part of the same, is a clear, true, and complete description of my invention.

In order that the mechanical features devised by me and the novel mode of operation involved in the use of my warpers may be fully comprehended in connection with the ends I seek to thereby attain, I will state that the beaming of yarn spun on mules in cops has heretofore involved the use of a spool-stand and spools, upon each of which yarn has been laid in the operation of spooling, as it was drawn from a stationary cop, by an endwise draft of the yarn in a line substantially parallel with the axis of the cop.

The warping of yarns from quill-bobbins as used in ring-frame spinning has heretofore in many cases involved the use of a skewer-stand and skewers, upon which said bobbins are fixedly mounted, so that the yarn is drawn therefrom through yarn-eyes on its way to the beam by an endwise draft of the yarn substantially parallel with the axis of the bobbin; but in some cases warps have been spooled preliminary to warping by backwardly rotating the ring-frame bobbins on which the yarn was spun; and also such bobbins have been mounted on skewers or spindles in a stand, and the yarn has been drawn therefrom on its way to the beam by backwardly rotating the bobbins; but in no instance known to me have the spindles or skewers thus used for supporting the bobbins been small enough nor properly shaped to enable them to receive a mule-cop, so that the latter could backwardly rotate thereon or therewith and yield slightly to the draft of the yarn; and although I hereinafter refer to ring-bobbins, and show such in my drawings, I do so merely for the purpose of illustrating how suitable cop-supporting spindles as used by me may also be used for supporting bobbins in a warping-machine.

The prior systems of beaming, wherein the yarn is drawn endwise either from a mule-cop or from a ring-frame bobbin, involve the intro-

duction of an extra twist into the yarn during its transfer from the cop to the beam, and this extra twist is put into the yarn during its transfer for the reason that in both cases the yarn is drawn off endwise from stationary bodies of yarn, and in lines substantially parallel with the axis of the cop or the ring quill-bobbin, as the case may be. It is well known that the bodies of yarn as furnished by the spindles, whether in the form of detachable cops or carried on the quill-bobbins, are more or less liable to become broken, so as to render the further delivery of yarn therefrom by the particular endwise draft referred to practically impossible, and consequently much waste occurs, for when a cop or a quill-bobbin thus fails to deliver more or less of the remaining yarn is usually thrown aside as waste, and to obviate this waste is the prime object of my present invention.

It is also well known that spool-stands occupy so much space that the large number of yarns ordinarily required for a beam, or even a half beam, cannot be drawn in at one operation; and a further object of my invention is to enable with coarse warps an ordinary beam to be filled, thereby greatly economizing not only in mill-space and in extra spooling-machines and extra warping-machines, but also in the cost of attendance both for spooling and warping.

I am well aware that the prior warpers hereinbefore referred to, which take yarn directly from ring-bobbins, enable more ends of yarn to be worked than when ordinary spool-stands are employed; but by reason of my invention I am enabled to occupy still less space in working a given number of ends, and to readily, with coarse yarns, for instance, work enough ends to enable at one operation a beam to be properly filled for weaving; and with some classes of yarn I am not only enabled to work a larger number of warps than can be worked from a spool-stand, but by obviating the labor and expense of spooling I am enabled to greatly reduce the cost of warping, and to reduce the waste from broken or damaged cops to a minimum.

In accordance with my invention I beam directly from the mule-cops; but instead of drawing the yarn therefrom while said cop remains fixed and non-rotative, as heretofore,

the yarn is drawn therefrom in lines substantially at right angles to their axes, and said cops are permitted to revolve backwardly during the draft of the yarn therefrom on its way 5 to the beam, and therefore the yarn is beamed without further twisting it.

My said invention consists in the combination, with warp-beaming mechanism, (of any approved type,) of a yarn-delivering stand containing 10 cop-supporting spindles, which yield slightly and permit a cop to rotate backwardly thereon or therewith during the draft of yarn from the cop on its way to the beam. These cop-supporting spindles occupy so little space 15 in their stand that three or four of them need occupy no more space than a single large spool as usually employed, and as compared with the prior bobbin-stands I can work about twice as many ends in a given space. The 20 backward rotation of the cops and their capacity to vary their position obviate their breakage and the consequent waste thereof, and for the first time, so far as my knowledge extends, I am enabled to place the yarn upon 25 a beam from cops in exactly the same condition as to twist that it was left in by the spindle. The cop-supporting spindles should be so proportioned, constructed, or arranged that they can be slightly bent, moved, or deflected 30 under the tension of the yarn, so that in the event of an imperfect cop said spindle will permit the cop to sufficiently change in position to enable the yarn to practically free itself from any ordinary break or snarl in the 35 cop. It will readily be understood that spindles which are small enough to properly receive and support a cop and permit it to rotate freely must of necessity be also capable of so receiving a bobbin as to permit said bob- 40 bin to freely rotate backwardly in the delivery of yarn therefrom.

To more particularly describe my invention, I will refer to the accompanying drawings, in which Figure 1 is a side elevation of one of 45 my improved beaming-machines or warpers. Fig. 2 is a rear view of a portion of the yarn-delivering stand of the machine. Figs. 3 to 6 illustrate different spindles suitable for my purpose.

50 The yarn-delivering stand A is a vertical rectangular frame, and it is provided with numerous horizontal bars, *a*, upon which are mounted a large number of cop-receiving spindles, *b*, and, wherever necessary, I provide yarn- 55 rods *c*, for securing a proper draft upon the yarn—*i.e.*, a draft substantially at right angles to the axis of the cops *d* when placed upon their spindles. These spindles must of necessity be somewhat longer than the cops, and for 60 the best results sufficiently smaller than the spindles on which the cops were formed to enable them to revolve freely thereon. As a rule, said spindles need be but little, if any, heavier than ordinary knitting-needles, and the more 65 flexible and yielding they are the better will they be suited for this purpose, provided they are capable of properly supporting a cop while

permitting it to freely rotate. Spindles which are in themselves stiff and practically inflexible may be employed with fairly satisfactory 70 results, provided they are small enough to leave the cop free thereon and have yielding foot-steps or head-bearings which will permit the spindle to yield slightly to the tension of the yarn, so as to enable the latter to better free 75 itself from any snarl or mat which may exist in the cop.

In an application for Letters Patent filed by me March 7, 1881, pertaining to the recovery of yarn from broken or injured cops, I have 80 shown and described several forms of spindles which are suited to my present purpose; and I am well aware that some spindles heretofore used for spinning have sufficient yielding capacity to warrant their use in accordance with 85 my invention.

In Fig. 3 of the present drawings the spindle *b* is inflexible; but it is provided with a yielding head-bearing and a yielding foot-bearing, and in this case the spindle may be such 90 as is used for spinning, and arranged to be readily detached from the mule and placed with its load of yarn directly into the warper, and instead of permitting the cop to rotate on said spindle, the latter, with the cop, will rotate 95 backwardly for the delivery of yarn to the beam.

In Fig. 4 the foot of the spindle is mounted in a close-fitting rubber socket, and although this spindle is one upon which the cop is 100 formed it is not rotated at its foot while in the beaming-machine, because it embodies a dead-spindle, *b'*, provided with a revolving sleeve, *b*², on which the cop is formed, and a whirl, *b*³, on said sleeve is used for rotating the sleeve 105 for spinning, the whole being readily removed from its seat in the spinning-machine, and as readily placed in the beaming-machine. With this form of spindle, mounted as shown, it will be seen that it can yield slightly to the tension 110 of the yarn because of the yielding socket, and also that the cop can be freely rotated backwardly with the sleeve in drawing the yarn therefrom.

In Figs. 5 and 6, I illustrate how laden ring-bobbins may be successfully mounted upon a small flexible non-rotative spindle like those shown in Fig. 1. A tapered metallic sleeve, *e*, has at its inner upper end a bearing, which rests upon the top or point of the slender spindle *b*, so that it can freely revolve thereon. The ring-bobbin *f* is placed over said sleeve *e*, so that the latter supports the bobbin at its upper end, thus enabling the bobbin and sleeve to be freely rotated backwardly in the delivery 125 of yarn. When thus mounted the upper end of the bobbin can be swung slightly to and fro under tension of the yarn, because of the flexibility of the spindle, and the lower end of the bobbin can also vibrate slightly, because the 130 interior of the lower end of the sleeve is larger than the spindle. If desired, the cops may be mounted upon tapered sleeves like that shown, and with them be mounted upon the spindles

b. I deem it preferable for the best results that long paper cop-tubes be used in spinning. Other illustrations of suitable cop-supporting devices might be given; but these are deemed ample for the purposes of this specification. In some cases, as when warping from bobbins, or from the revolving metallic tapered tubes, or from the spindles on which the cops were formed, it is desirable to employ therewith 10 friction devices for preventing them from rotating too freely or rapidly under the draft of the yarn therefrom.

It is to be distinctly understood that although I have described and illustrated ring-frame bobbins as delivering their yarn directly to the beam my invention includes only such spindles as by reason of their form and dimensions enable them to be used as cop-supporting spindles, and that I have described and 20 illustrated ring-frame bobbins as used therewith to show that spindles capable of receiving a cop, as described, and enabling the delivery of the yarn by a backward rotation of the cop can, if desired, also be used with approximately desirable results for supporting 25 ring-frame bobbins and having the yarn properly delivered therefrom to a beam in a warping-machine.

The beam B is mounted and rotated substantially as heretofore, and the yarn from the stand passes through the combs or reeds g and h, and between said combs are tension-rolls i and drop-wires k, these latter being portions of the usual stop-motion for stopping the machine when a yarn breaks. It will be seen that the yarn when thus placed upon the beam is in the same condition as to twist that it was when on the spindle; and while I do not assert that an extra twist is always objectionable in

warps, I prefer that all the twist be put in by 40 the spindles, because then the yarn is twisted evenly, whereas in warping as heretofore the extra twist is unevenly applied, because of the gradual reduction in the diameter of the cop from which the yarn is drawn. It will also be 45 seen that the spindles are inclined rearwardly for enabling cops to be readily placed thereon, and that they are capable of being placed so closely together side by side that an unusually large number of ends may be readily provided 50 for in one yarn-stand.

In drawing off the yarn from cops in the manner described a cop is seldom injured, whereas by drawing the yarn, as heretofore, from a stationary cop and over its end damaged cops are of frequent occurrence. 55

It is generally advisable that a small cop-stand be provided on top of the warper at its rear end, as shown, in order that an end from one or more of the cops thereon may be employed in case threads break or run out from the main cop-stand, thus assuring the full 60 number of threads on a beam.

Having thus described my invention, I claim as new and desire to secure by Letters Patent— 65

The combination, substantially as hereinbefore set forth, of the beam, its driving mechanism, the tension device, and a yarn-delivering stand provided with a series of cop-supporting spindles which are adapted to slightly yield 70 under the tension of the yarn and permit cops to be backwardly rotated thereon or therewith, as set forth.
